UNITED STATES PATENT OFFICE.

JOHN WEIRICK, OF BUCYRUS, OHIO.

FENCE.

SPECIFICATION forming part of Letters Patent No. 771,957, dated October 11, 1904.

Application filed May 20, 1904. Serial No. 208,927. (No model.)

To all whom it may concern:

Be it known that I, JOHN WEIRICK, a citizen of the United States, residing at Bucyrus, in the county of Crawford and State of Ohio, 5 have invented certain new and useful Improvements in Fences, of which the following is a specification.

The primal purpose of this invention is to securely and firmly brace the terminal post, 10 so as to resist the tension upon the line wires or strands, the bracing means being of such arrangement as to obviate encroachment upon adjacent territory.

In accordance with this invention a post is 15 located along the prescribed line of fence a short distance from the terminal post to be braced, and a timber firmly connects the lower ends of the terminal and stay posts below the surface of the ground, and its end portions, 20 which project beyond said posts, receive stay- plates upon which the earth is tamped, a diagonal brace connecting the lower end of the supplemental post with the terminal post near the ground-line, all as will appear more fully 25 hereinafter.

The invention consists, essentially, of the novel features and details of construction clearly set forth in the subjoined claim and illustrated in the drawings hereto attached, 30 in which—

Figure 1 is a side elevation of a fence embodying the invention. Fig. 2 is a perspective view of the terminal and supplemental posts having the fence-wires attached thereto and braced in accordance with this invention. 35

Corresponding and like parts are referred to in the following description and indicated in both views of the drawings by the same reference characters.

The post to be stayed, and designated as the “terminal” post, is indicated by the reference-numeral 1, and the supplemental post co-operating therewith is indicated by the reference-numeral 2. These posts 1 and 2 may be 45 arranged at the end of a line of fencing or adjacent to an opening therein, the purpose be-

ing to brace post 1 against the tension upon line-wires 8, secured thereto and to the remaining fence-posts. Supplemental post 2 is 50 arranged a short distance from post 1—about six feet, more or less—both posts having their lower portions planted in the ground the usual depth and connected at their lower ends by means of timber 3, which is preferably mortised into a side of the posts and has its end portions extended beyond same a short distance to receive short plates or boards 4, arranged transversely thereof and resting thereon. These plates or boards 4 serve to prevent 55 vertical displacement of timber 3 by having the earth packed thereon. Brace 5 is interposed diagonally between the lower end portions of posts 1 and 2 with its lower end bearing against the foot of post 2 and its upper 60 end bearing against and secured to post 1 about at a point corresponding with the ground-line. An inward pull upon the upper end of terminal post 1 is resisted by brace 5 and timber 3. Hence the strain upon the line 65 wires or strands 8 cannot effect displacement of terminal post 1. Brace 5 and timber 3 are 70 in the plane of the fence, hence are well adapted to resist strain of the fence-wires upon post 1. The braces indicated by the 75 dotted lines 6 and 7 of Fig. 1 are temporary stays to fix the position of posts 1 and 2 when applying parts 3 and 5 and are removed after said parts 3 and 5 are properly positioned. After the posts 1 and 2 have been properly 80 set and braced, the earth is tamped about parts 3, 4, and 5, the fence-wires being attached to the posts along the line of inclosure in the usual way.

Having thus described the invention, what 85 is claimed as new is—

In a fence, the combination of a terminal post, a supplemental post located a short distance from the terminal post, both posts having their lower end portions planted in the 90 ground, a longitudinal timber firmly attached to the lower ends of the terminal and supplemental posts and having its end portions extended, transverse plates arranged upon the

projecting ends of the longitudinal timber, and a brace in the plane of the posts and timber, having its lower end resting against the foot of the supplemental post in the angle formed between said post and longitudinal timber, and having its upper end connected to the terminal post at or near the ground-line, said brace, longitudinal timber and trans-

verse plates being arranged wholly below the ground, substantially as set forth. 10

In testimony whereof I affix my signature in presence of two witnesses.

JOHN WEIRICK. [L. s.]
